STORAGE TANK

Bruce P. McDaniel and Hiram E. Gingrich, Bethlehem, Pa., assignors to McClintic-Marshall Corporation, a corporation of Pennsylvania

Application April 6, 1935, Serial No. 14,992

6 Claims. (Cl. 220—1)

This invention relates to storage tanks for oil, volatile liquids, and gases, and more particularly to the roof construction for such tanks.

Storage tanks of the type referred to are sealed against vapor losses and it is necessary to provide means for taking care of the physical variations in the accumulated gases in the top of tank due to changes in temperature with the consequent changes in volume or pressure. It is possible to make the tank structure such as to resist any gas pressure changes due to temperature changes but costs for such structures are prohibitive and the more economical design is one which combines provision for changes in volume with a reasonable maximum pressure change. The latter condition may be had by having expandable means which comprises the roof structure in such a manner that the weight of the roof determines the maximum unit pressure allowable and a tendency for higher pressures is counteracted by movement of the roof proper to increase the sealed volume of the storage tank.

It is an object of our invention to provide an expandable leak-proof joint of considerable capacity between a storage tank and its roof.

It is a more specific object of our invention to provide an expandable leak-proof joint of a bellows type between a storage tank and its roof in such a manner that changes of sealed volume within the tank due to expanding gases shall be under a predetermined maximum pressure and that such volumetric changes shall be of considerable amount.

Other objects and advantages will be apparent from the following description, wherein reference is made to the accompanying drawings illustrating the preferred embodiment of our invention.

Fig. 1 is a view in elevation and part section of a storage tank embodying our invention;

Fig. 2 is a detail section showing a modification embodying our invention;

Fig. 3 is a detail section showing another modification embodying our invention in its normal collapsed condition; and

Fig. 4 is a detail section showing the relation of parts of the modification shown in Fig. 3 when expanded under pressure of the contained gases.

It is to be understood that the drawings are conventional and diagrammatic in form and that detail structure of the tank is not shown. For instance, it is standard practice, due to the size of the tank, that the body and roof of the tank be made up of a plurality of plates joined together either by riveting or welding, or there may be piping and safety appliances used, but as none of

these features have any bearing on our invention they are not shown.

Referring now to Fig. 1 of the drawings, we show diagrammatically a storage tank structure embodying the features of our invention when in its normal collapsed condition. The storage tank 10 may be of any suitable design, but is preferably cylindrical and usually comprises a tank bottom 11, a curb ring 12, a tank body 13, and a roof 14. In this embodiment of our invention the roof 14 comprises a roof plate 15, a bellows ring 16, a tank roof connecting ring 17, tank connecting ring 18, and suitable fastening devices 19, 20, 21, and 22, used to join the contiguous edges of the various parts one to another as shown.

While we prefer rivets, as shown, for fastening devices, any suitable form of fastening device such as bolts or autogenous welding may be used without departing from the spirit or intent of our invention.

By the arrangement just described it will be seen that we have provided a form of bellows connection between the roof plate 15 and the tank body 13 by reason of the roof plate 15 being attached to the bellows ring 16, by means of the fastening devices 19, at their outer circumferential edges; and by attaching the bellows ring 16 to the tank roof connecting ring, by means of the fastening devices 20, at their inner circumferential edges; and by attaching the tank roof connecting ring at its outer circumferential edge to the tank body 13 through the medium of the tank connecting ring 18 and the fastening devices 21 and 22. The joints made by the fastening devices 19 to 22, inclusive, are assumed to be leak-proof—caulking being resorted to if necessary.

The roof plate 15, the bellows ring 16, and the tank roof connecting ring 17 are to be made up of standard rolled steel plates suitably joined together in any of the well known methods of riveting, bolting, or welding. The tank connecting ring 18 is preferably made of a standard rolled steel angle section.

In addition to the parts already enumerated we provide also a supporting structure 23 to support the roof 14 in its normal collapsed position as shown in Fig. 1. This roof supporting structure 23 may be of any suitable design of material, although we prefer to construct it of structural steel.

In Fig. 2 we show a modification of our invention which we use where a greater range of flexibility and variation in volumetric changes are required than can be utilized from the ar-

angement shown in Fig. 1. The arrangement and function of parts in Fig. 2 is practically identical to that shown in Fig. 1 with the exception that we have added two additional bellows rings. 5 In this embodiment of our invention the roof 14 comprises a roof plate 24, an upper bellows ring 25, an intermediate bellows ring 26, a lower bellows ring 27, a tank roof connecting ring 28, a tank connecting ring 29, and a tank body 30. 10 Suitable fastening devices similar to those shown in Fig. 1 are used to attach the contiguous edges of the various parts together and need not be enumerated. It will be noted in Fig. 2 that we have arranged the diameter of the various plate 15 members and their rivet circles in such a manner that when the assembled roof is collapsed the rivet circles nest together without interference, and that we preferably maintain the outer diameters of the roof plate 24 and the upper bellows ring 25 greater than that of the underlying 20 rings and for drainage purposes.

In Fig. 3 we show still another modification of our invention. In this arrangement we have the roof plate 31, an upper bellows ring 32, a lower 25 bellows ring 33, a tank roof connecting ring 34, a tank connecting ring 35, a tank body 36, and a roof supporting structure 37. Suitable fastening devices similar to those described for Figs. 1 and 2 are similarly used. It will be noted that in this 30 modification the point of attachment of the roof plate 31 to the upper bellows ring 32 occurs at the inner circumferential edge of the bellows ring, and that the outside diameter of the roof plate 31 is maintained greater than that of the 35 bellows rings. The latter condition is not necessary, but we prefer it in order to give protection to the underlying bellows rings and to gain a certain amount of added rigidity in the roof plate 31.

40 In Fig. 4 we show approximately the relative position taken by the various parts shown in Fig. 3 when under maximum allowable pressure and excess volume, and is illustrative of the action that occurs under similar conditions in the hereinbefore described structures shown in Figs. 1 and 2.

It is obvious that the unit pressure that the 45 roof 14 will resist before expanding is contingent upon its movable weight, its projected area subject to pressure, and a certain resistance to flexure in the bellows and tank roof connecting rings. We prefer to keep the resistance to flexure low and for this reason we make the bellows ring and the tank roof connecting ring of thinner 50 sheets than the roof plates. It is also obvious that the range of expansion after the weight of the roof has been overcome by the expanding gases is dependent upon the number of bellows rings included in the roof assembly. Therefore, the relative thickness of the plates and the number of bellows rings required will be contingent 55 upon the exigencies of the type of service for which it is designed, and will vary for the same type of tank in different parts of the world.

60 It is now evident to those skilled in the art that, by the described construction, we have provided in storage tank roof construction a leak-proof expandible joint containing valuable and novel improvements. By utilizing standard rolled 65 steel plates and structural sections we have not only an economical design but one that is efficient from a safety standpoint and is durable. Our design lends itself to the use of any of the 70 approved methods of steel plate jointure such as riveting, bolting, or welding, making it possible to 75

utilize the same method throughout the structure of the entire tank when desirable. The design itself is flexible in that the expansive capacity of a tank may be readily altered after construction by the addition or elimination of 5 bellows rings, this being particularly true where welding is the jointure means.

It will be apparent to those skilled in the art that although we have shown the preferred embodiments of our invention in the hereinbefore described arrangements that still other arrangements could be used without departing from the spirit of our invention.

Having thus described our invention what we claim as new and desire to secure by Letters Pat- 15 ent is:

1. A storage tank comprising a tank body, a roof supporting structure, a rolled steel plate roof normally sustained by said roof supporting structure, and a metallic bellows connecting leak- 20 tight the said tank body to said roof, said metallic bellows comprising a plurality of rolled steel plate rings connected circumferentially alternately at their inner and outer peripheries the said plate rings being unitary in structure and 25 normally in close stacked relationship with said roof.

2. A storage tank comprising a tank body, a roof supporting structure, a rolled steel plate roof normally sustained by said roof supporting 30 structure, a rolled steel plate ring having its outer circumferential edge attached to the upper periphery of the tank body, and a second rolled steel plate ring interposed between the first mentioned plate ring and the said roof and 35 having its outer circumferential edge attached to said roof and its inner circumferential edge attached to the inner circumferential edge of the first mentioned plate ring, the said plate rings being unitary in structure and normally in close 40 stacked relationship with said roof.

3. A storage tank comprising a tank body, a roof supporting structure, a rolled steel plate roof normally sustained by said roof supporting structure, and a plurality of superimposed rolled 45 steel plate rings joined together alternately at their inner and outer circumferential edges and the uppermost plate ring having a circumferential edge joined to the roof and the lowermost plate ring having a circumferential edge joined 50 to the upper peripheral edge of the tank body, the said plate rings being unitary in structure and normally in close stacked relationship with said roof.

4. A storage tank, comprising a tank body, a roof supporting structure, a rolled steel plate roof normally sustained by said roof supporting structure, and a plurality of superimposed rolled steel plate rings joined together alternately at their inner and outer circumferential edges and the 60 uppermost plate ring having a circumferential edge joined to the roof and the lowermost plate ring having its outer circumferential edge joined to the upper peripheral edge of the tank body, the said plate rings being unitary in structure 65 and normally in close stacked relationship with said roof.

5. A storage tank for volatile liquids comprising a rigid tank body for holding the liquid, a steel roof for the tank, a metallic bellows fixed at 70 its lower periphery to said tank body and fixed at its upper periphery to said roof, said metallic bellows comprising a plurality of rolled steel plate rings connected circumferentially alternately at their inner and outer peripheries, and means 75

located within said rigid tank body for supporting the weight of the roof and bellows when said bellows is in the collapsed condition.

6. In a storage tank for volatile liquids, an expansion roof therefor comprising an outer ring portion secured around the outer periphery thereof to the wall of the tank, a central plate portion, and means securing the central plate portion to said outer ring portion to permit the central plate portion to move upwardly upon abnormal pressure in the tank to thereby increase the vapor space in the tank, said means including

a plurality of intermediate overlapping rings and which slope in opposite directions as regards adjacent rings when the roof is expanded, the inside diameter of certain intermediate rings progressively decreasing in an upward direction to render the joints thereof accessible for repair, and supporting structure in the tank for sustaining the roof in a substantially horizontal plane when normal pressure exists within the tank.
